UNITED STATES PATENT OFFICE

168,383

JET PLANE KITE

Kenneth C. Smith, Anderson, Ind.

Application June 23, 1952, Serial No. 20,308

Term of patent 3½ years

(Cl. D34—15)

To all whom it may concern:

Be it known that I, Kenneth C. Smith, a citizen of the United States of America, residing at Anderson, in the county of Madison and State of Indiana, have invented a new, original, and ornamental Design for a Jet Plane Kite, of which the following is a specification, reference being had to the accompanying drawing, forming part thereof.

The single figure is a perspective view of a jet plane kite, showing my new design.

I claim:

The ornamental design for a jet plane kite, as shown.

KENNETH C. SMITH.
